IGNITION SYSTEM FOR GAS OR LIQUID FUEL APPLIANCES

Birchard L. Matthews and Edward J. Zarybnicky,
Cleveland, Ohio, assignors to The W. J. Schoenberger Company, Cleveland, Ohio, a corporation of Ohio

Application June 29, 1945, Serial No. 602,242

4 Claims. (Cl. 158—117.1)

1

This invention relates to safety control and ignition systems for gas or liquid fuel heating or cooking appliances employing a main burner.

It has been common practice to employ a pilot light or other ignition means, such as a hot wire or spark, for lighting the main burner of such appliances but much difficulty has been experienced with the safety controls employed with these pilots due to the adverse effect which ambient heat has had upon such prior controls.

One of the principal objects of the invention is to reduce the hazards encountered with prior safety pilot controls incident to current failure, fuel failure, or extinguishment of the pilot light.

Another object is to provide positive fuel shut-off in case of pilot extinguishment, which will not be interfered with by the heretofore troublesome factor of ambient heat.

It is a further object of the invention to provide for fuel shut-off to the main burner when the height of the pilot flame has decreased to such an extent that it does not give instant ignition, as in the case where delayed ignition results from the pilot orifice slowly closing off due to foreign matter in the fuel.

Still another object of the invention is to provide an automatic ignition system in which a time interval will occur between the lighting of the pilot and the ignition of the burner, thus assuring the person lighting the pilot sufficient time to perform this operation and remove his hand from the combustion chamber before fuel is allowed to flow to the main burner.

A still further object is to provide a photo-cell ignition system for a gaseous liquid fuel appliance in which the life of the photo-cell is extended to a maximum degree.

Other objects and advantages will be in part described and in part obvious as the description is considered in connection with the accompanying drawings, in which:

Figure 1 is a horizontal sectional view of the top portion of a gas range equipped with the improved ignition system;

Figure 2 is a sectional view of the electrically operated control valve;

Figure 3 is a sectional view of a modified form of ignition pilot for the main burner; and

Figure 4 is a diagrammatic view of the electric circuit employed in the system.

Referring more particularly to the drawings wherein, for the purpose of convenience, we have shown our improved ignition system applied to a conventional gas range 1, having a main enclosed oven burner 15 for which, in this particu-

2

lar embodiment of the invention, safe ignition is to be provided. The range 1 comprises a top burner section or compartment 2, and an oven burner section or compartment 3, separated by a double division wall 4. Suitably mounted in the section 2 are the front and rear top burners 5 and 6, respectively, to which gas is supplied from a manifold 7, valves 8 and 9 on the manifold being employed to regulate the flow of fuel to and through the top burner mixing tubes 10 and 11. A constant burning pilot 12, which receives a continuing supply of gas from a supply pipe 13, extending between the manifold 7 and pilot 12, provides for the ignition of top burners 5 and 6, through the medium of flash tubes 14.

The main enclosed oven burner 15 gets its ignition from a sub-burner or pilot 16, having communication with the constant burning pilot 12, through the medium of a flash tube 17. A pipe 18 connected at one end to a manually controlled shut-off valve 19 mounted on and communicating with the manifold 7 and at its other end connected to and supporting main burner pilot 16, supplies gas to the latter when valve 19 is in open position, while the mixing tube 25 of main burner 15 receives its supply through shut-off valve 19, pipes 20, 21 and 22.

The pilot 16 extends from adjacent to the main burner 1, to a point just outside the oven housing 26, where it is connected with the flash tube 17 extending between the pilots 12 and 16. Consequently when gas is supplied to the main burner pilot 16, a portion of the gas supply will be injected through the flash tube 17 and ignited by the constant burning pilot 12. After the ignition takes place at one end of the sub-burner or pilot 16, gas will burn throughout its entire length thus causing the main burner to be ignited.

A conventional thermostatic valve 23, supported in the front wall 24 of the range 1 and connected to a thermo bulb 27, positioned within the oven 3, is interposed between the pipes 20 and 21 for automatically regulating the oven temperature, without interfering with the manual valve 19 for manually turning the oven burner 15, on or off, as well as for manually controlling the flow of gas to pilot 16.

An electrically operated control valve 28, described in more detail hereinafter, also positioned in the main supply line between the fuel supply pipes 21 and 22, automatically controls the flow of gas to the main burner 15 but not to the sub-burner or pilot 16. A photo-electric tube 100 and housing 29 therefor is located outside the oven or combustion chamber 3, in the space 30 between

the division walls 4, and a light tube 31, is positioned between the photo-tube 100 and the ignition pilot 16, for directing light from the pilot flame to the photo-tube 100. The end of the light tube adjacent to the pilot flame 32 of pilot 16, is rigidly supported in a bracket 33, with respect to the pilot so that, in the event the pilot decreases in height, beyond a predetermined safe height for positive ignition, the flame 32 will no longer appear across the opening at that end of the tube, as illustrated in Figure 1. However, in the Figure 3 modification, embodying a single port ignition pilot 16', a light tube 31' is adjustable, as to height, with respect to the pilot flame 32'. We accomplish this by supporting the light tube on one end of a bracket 33', the other end of which is adjustably confined between lock nuts 34 and 35 threadedly mounted on the outlet end of ignition pilot 16'. This enables the operator to accurately position the restricted orifice 36 of light tube 31' with respect to the pilot flame, so that the moment the latter drops below the opening the device will be shut off. The opening 78 in bracket 33', through which the outlet end of pilot 16' extends is of sufficient size and the pipe 18 is sufficiently resilient to permit slight raising or lowering of the pilot through the bracket when the lock nuts 34 and 35 are appropriately manipulated.

Suitably secured to the back wall of range 1, remote from the combustion or oven chamber 3, as by bolts 37, is a housing 38, for containing an amplifying tube 39, relay 40 and transformer 41 which, together with the solenoid valve 28 and photo-tube 100, receive current from a 110 volt source of supply 43, through the medium of wiring about to be described. The operation of the system is as follows:

Assuming that the constant-burning pilot 12 for the top burners has been ignited, its source of fuel being in no way impaired by the controls of the oven ignition system, and that the valves 19 and 23 are in full open position, this would allow fuel to flow in the main burner supply line up to, but not beyond, the electric control valve 28. It also would provide a source of fuel supply to the sub-burner pilot 16 or the single port ignition pilot 16', as the case may be. A portion of the fuel thus supplied would be directed up the flash tube 47 and be ignited by the constant-burning pilot 12. The ignition would occur at the external end of the sub-burner 16 and carry over to the opposite end of the sub-burner located adjacent to the main burner 15 and also adjacent to the light tube 31. The pilot 16 burning in front of the light tube 31 actuates the photo-cell 100 which, in turn, allows current to be passed through the amplifier tube 39, thereby actuating the relay 40 which operates the electric control valve 28. This valve then assumes an open position, allowing fuel to be supplied to the main burner 15 which is ignited by the sub-burner 16.

The photo-cell 100 will continue allowing current to flow through the amplifying tube as long as the main control valve 19 remains in an open position so that fuel can be supplied to the sub-burner 16. When the main valve 19 is closed, the sub-burner 16 is extinguished and the light source is removed from the light tube 31, thereby preventing the amplifying tube 39 from supplying current to the relay, which assumes an open position and causes the electric control valve 28 to shut off. When a thermostatically controlled valve, such as the valve 23, is also placed in the

main fuel line, the system can continuously function in response to the temperature of the combustion chamber.

In the event of fuel failure, there will be no light source 16 in front of the light tube 31 which prevents the electric control valve 28 from opening. If the valve 28 is in an open position at the time of fuel failure, it will immediately assume a closed position. Furthermore, in the event of electric power failure, the solenoid valve 28 will also close. If the appliance had been in operation at the time of power failure, it will automatically resume operation when the current supply is resumed. In this case, the constant-burning pilot 12 has not been extinguished and the sub-burner 16 has either continued to burn or can be ignited. Upon resumption of the power, therefore, the sub-burner 16 will at once actuate the photo-tube 100 and thereby automatically effect ignition of the main burner 15. It will be understood that when the electric power is on the coil 44 of electric valve 28 will be energized thus causing the plunger 45 to be lifted from its seat 46, against the tension of spring 42, to place the inlet opening 47 in communication with outlet opening 48.

Having reference to Figure 4, it will be noted that the diagram there shown consists of a photo-tube 100 controlling the current flow through amplifying tube 39. The amplifying tube 39 operates the relay 40 which, in turn, controls the operation of the solenoid valve 28. The photo-tube 100 is a two-element tube having a cathode 49 and an anode 50. The amplifying tube 39 has an anode 51, commonly known as the plate of the tube, a cathode 52, and a grid 53.

In the circuit shown, the three-step 110 volt A. C. transformer 41 is used to supply the proper voltage to the various parts in the circuit. A voltage of approximately six volts is taken from the transformer between the points 54 and 55 to supply current for cathode heating. The proper voltage for the plate circuit is taken from the transformer 41 between the connections 56 and 54. The voltage required for the grid circuit is taken from the transformer between the points 55 and 57. A resistance 58 and a condenser 59 are connected in the grid circuit as shown. The photo-tube 100 is connected across the grid 53 and the plate 51 of the amplifying tube 39. The photo-tube 100, as previously described, is connected so that it will pass current when a light source is directed on to it.

The photo-tube 100 illustrated is an emissive type of tube such as the PJ-23 or 930 put out by the General Electric Company. The amplifying tube 39 is a common low power radio receiving type of tube. It is not the intent of this descriptive material, however, to limit the device to these particular types of tubes.

In the device shown, which includes a common type of amplifying circuit, the photo-tube 100 will not pass current unless it is receiving a beam of light. The amplifying tube 39 will not pass current except under proper conditions of negative charge on the grid 53. Using this type of amplifying tube, a negative charge or bias is maintained on the grid 53 to prevent current flow across the plate circuit from cathode 52 to plate 51 until such time as the current flow is desired. The resistance 58 is included in the circuit to obtain the desired negative charge on the grid 53. The purpose of the grid condenser 59 is to decrease the grid bias required to reduce the plate 75 current to a given value when the photo-cell is

dark. The negative grid voltage is out of phase with the plate voltage when high values of grid resistance are used, thus making ineffective the grid control. This is due to the input capacity of the tube in combination with the grid resistance. The condenser 59 brings more nearly in phase the effective grid bias and the plate voltage.

The primary coil 60 of the transformer 41 is connected to the house currents. When the system is put into use, therefore, current flows from the secondary coil 61 at 57 through wire 62, grid resistance 58 and wires 63 and 64 to condenser 59 and will continue to flow until the latter is charged. After the condenser charge has reached equilibrium, there is no voltage drop in the grid circuit as long as the photo-tube is dark, as there is no flow of current from the grid 53 of the amplifying tube 39. Since the grid 53 is connected to the resistor 58 and condenser 59 thru wire 65 a negative bias or charge is maintained on the grid 53 of sufficient magnitude to prevent electrons flowing from the cathode 52 to plate 51 of tube 39. It will also be seen that current at the same time flows from the low voltage point 55 thru wire 66, cathode heater 52 and returns by wire 67 to transformer 41 at point 54 and brings the cathode 52 up to the required temperature for operating the amplifying tube 39. The very low resistance type relay 40 is installed in the plate circuit between the plate 51 and the transformer connection 56. To operate this relay, it is necessary to have a current flow in the plate circuit of the amplifying tube 39.

By igniting the constant-burning pilot light 12, a source of light is directed onto photo-tube 100. Electrons will then flow from wire 65 thru wire 68 to cathode 49, across photo tube 100 to anode 50 and thence thru wires 69 and 70, relay 40, and wire 71 to transformer tap 56, this current not being sufficient to operate relay 43. This flow of current thru the photo-tube 100 lessens or decreases the negative bias that had been maintained on grid 53 which immediately allows electrons to flow thru the amplifying tube 39 from the cathode 52 to the anode or plate 51. The plate circuit then has current flowing from the transformer tap 55 thru conductor 66, amplifying tube 39, fuse 72, relay 40, and back to transformer connection 56. This current flow will actuate relay 40 so as to "make" contacts 73 and 74. Current will then flow from the 110 volt source 43 thru wire 75 contacts 74 and 73, wire 77 thru coil 44 at solenoid valve 28 and thence back thru wire 76 to said source 43. The coil 44 will then be energized, magnetically raising valve plunger 45 against the pressure of spring 42, thus opening passageway 46 of valve 28 and permitting fuel to flow to main burner.

When the photo-tube 100 is illuminated, it acts as a resistance in the circuit, and when passing current through the photo-tube to reduce the negative bias on the grid 53, a delay in the reduction of negative bias is caused until the condenser discharges. It is seen, therefore, that there is a time factor directly related to the resistance flow of the photo-tube and the size of the grid condenser, delaying the action of the amplifying tube 39 and the actuation of the relay 40. This delay time factor is a product of the resistance of the photo-tube in megohms and the condenser value in microfarads. By using the proper size condenser, it is possible to get a delay action on the operation of the relay of from a few seconds to as long as four or five

minutes. It is apparent that, without a time delay on the starting of the cycle, the device would operate so quick that gas would be allowed to flow to the main burner the instant that a flame from a match was placed in front of the light tube when igniting the pilot. A delay in the starting cycle of sufficient time to allow the person to ignite the pilot and withdraw his hand from the combustion chamber is therefore highly desirable.

Extinguishment of constant-burning pilot 12 instantly stops the flow of electrons between the cathode 49 and the anode 50 of the photo-tube. The negative bias on grid 53 of the amplifying tube 39 is immediately raised, and thereby instantly cuts off electron flow from the cathode 52 to the anode 51 of the amplifying tube, thereby causing relay 40 to open contacts 74 and 73 shutting off current flow to the solenoid valve 28, which then assumes a closed position, stopping the flow of gaseous fuel to the main burner. It is seen, therefore, that pilot extinguishment or fuel cut-off will instantly cause the ignition system to assume a safe condition by shutting off the flow of fuel to the burner. And, should the current fail, the relay 40, which is normally in an open position, immediately assumes this position.

In the event of failure of the life of the photo-tube no electrons will pass across its cathode 49 to its anode 50 and, as explained above, the negative bias on grid 53 is immediately raised, thereby stopping flow of electrons from the cathode 52 to the anode 51 of the amplifying tube. It is seen, therefore, that in the event of failure of the life of the photo-tube 100 the system will operate to a safe condition, as no current will flow to the relay 40 it will assume an open position and shut off the solenoid valve 28.

It is also apparent that, in the event of failure of the life of the amplifying tube 39, there can be no current flow from the plate circuit of the tube which results in the relay assuming its open position and causing the solenoid valve 28 to close.

The fuse 72 is installed in the plate circuit as shown. This is to make the system safe in the event of a short circuit of the photo-tube. If the photo-tube is short circuited, a heavier flow of current results in the plate circuit. A fuse, therefore, can be properly sized in the plate circuit to blow if current in the circuit is raised above a predetermined value.

It will be noted that by having the photo-tube 100 responsive to a secondary pilot, it is not subject to light rays except when the appliance is in use. Consequently the tube is not deteriorating when the appliance is not in use.

Having thus described our invention, what we claim is:

- An ignition system for a gaseous or liquid fuel appliance having a fuel supply source, a main burner, a constant-burning pilot remote from main burner, an ignition pilot adjacent to the main burner, a flash tube positioned between the remote pilot and the ignition pilot for lighting the ignition pilot when it receives a supply of fuel, an electrically operated control valve controlling the flow of fuel to said main burner from said source of supply, a photo-electric cell so located as to receive and be responsive to the light from the ignition pilot, and actuating means responsive to the photo-cell for operating said electric main control valve said actuating means including a delay means to prevent the actuating

means from opening the electric valve until a predetermined time interval has elapsed after lighting the pilot.

2. An ignition system having a main fuel source, a main burner, a constant-burning pilot remote from the said main burner, an ignition pilot located adjacent to said main burner, a shutoff valve in the fuel supply controlling the gas to the main burner and the ignition pilot, a flash tube positioned between the remote pilot and the ignition pilot for lighting the ignition pilot when it receives a supply of gas, an electrically operated main control valve in the fuel supply line, for controlling the flow of fuel to said main burner, a photo-electric cell responsive to the flame of the ignition pilot, a light tube between the ignition pilot and the photo-electric cell, actuating means responsive to the photo-cell for opening the electric valve, said actuating means including a delay means to prevent the actuating means from opening the electric valve until a predetermined time interval has elapsed after lighting the pilot.

3. An ignition system having a main fuel source, a main burner, a constant-burning pilot remote from the said main burner, an ignition pilot located adjacent to said main burner, a shutoff valve in the fuel supply controlling the gas to the main burner and the ignition pilot, a flash tube positioned between the remote pilot and the ignition pilot for lighting the ignition pilot when it receives a supply of gas, an electrically operated main control valve in the fuel supply line, for controlling the flow of fuel to said main burner, a photo-electric cell responsive to the flame of the ignition pilot, a light tube between the ignition pilot and photo-cell positioned with respect to the ignition pilot so that if the pilot decreases in height beyond a predetermined safe height for positive ignition light rays cannot be received by the photo-cell, actuating means responsive to the photo-cell for operating said electric main control valve, said means including a delay means to prevent the electric control valve from opening until a predetermined time interval has elapsed after lighting the pilot.

4. An ignition system having a main fuel

source, a main burner, a constant-burning pilot remote from the said main burner, an ignition pilot located adjacent to said main burner, a thermostatically operated temperature control valve in the fuel supply controlling the fuel to the main burner, a flash tube positioned between the remote pilot and the ignition pilot for lighting the ignition pilot when it receives a supply of fuel, an electrically operated main control valve in the fuel supply line for controlling the supply of fuel to said main burner, a photo-electric cell responsive to the flame of the ignition pilot, a light tube between the ignition pilot and the photo-electric cell, actuating means responsive to the photo-cell for operating said electric main control valve, said means including a delay means to prevent the electric control valve from opening until a predetermined time interval has elapsed after lighting the pilot.
